UNITED STATES PATENT OFFICE.

ARCALOUS WYCKOFF, OF ELMIRA, NEW YORK.

WATER-PIPE.

Specification of Letters Patent No. 32,100, dated April 16, 1861.

To all whom it may concern:

Be it known that I, ARCALOUS WYCKOFF, of Elmira, in the county of Chemung and State of New York, have invented a new 5 and Improved Water-Pipe; and I do hereby declare that the following is a full, clear, and exact description thereof, reference being had to the accompanying drawings, making part of this specification.

Figure 1 is a view in perspective, of a joint of my improved water pipe, of small or merchantable size, a portion of the outer covering of cement being removed, to show the coiling of the metallic band around the 10 wooden tube; Fig. 2, a central longitudinal section of two joints of the wooden tube or pipe, united; also a detached view in perspective, of the wooden thimble by which the joints are united; Fig. 3, a view (corresponding with Fig. 1) in perspective of a 15 portion of the water pipe of large size, to be finished only as laid in the trench prepared for its reception in the ground. Fig. 20 4 a transverse section, exhibiting the pipe as laid in the trench.

Like letters designate corresponding parts in all the figures.

The object of my invention is to construct a water pipe which shall retain the advantages of unequal cheapness and perfect 30 cleanliness and salubrity of wooden pipes, and also possess the requisite tightness, strength and durability sought for, in using iron or any other kind of pipes.

In order to retain the cleanliness and wholesomeness of the wooden pipe, I make 35 of wood the interior of the new water pipe, or all which comes in direct contact with the water. To secure the requisite strength, I wind the wood with iron or other metallic 40 band. For securing the necessary tightness at the joints, I employ interior thimbles of wood, which close the joints tight by the permanent swelling of the fibers with the 45 water itself. The desired durability is effected in part, by the outer coating of cement, and partly by the incessant saturation of the wood with the water; and this uninterrupted saturation is accomplished by the 50 extraordinary thinness of the wood rendered feasible by the use of the winding band and exterior cement. And the additional cost 55 the metallic band and exterior cement is in great measure, compensated by this superior thinness of the wood, in greatly economiz-

ing the material of the wood itself, thereby maintaining a cheapness of construction unattainable by any other kind of water pipe known.

The interior wooden pipe A, when 60 strengthened by the metallic band B, and cement covering C, is required to be but little if any thicker than ordinary iron pipes of the same diameter are; but it is proper to proportion it somewhat to the head or pressure of water, to which it is to be subjected. And whatever may be wanting in the strength of the wood, is to be supplied by the strength of the iron or other metallic band. The cement covering C, also adds 65 70 more or less to the actual strength of the pipe, yet it may not be best to rely on this in calculating the strength required.

In order that the thinness of the wood may be taken full advantage of, in economizing the material, I cut the wooden pipes from the timber by means of annular augers, many improvements in which I am the inventor or possessor of. These augers, in 75 80 boring a pipe, cut only a comparatively thin kerf, leaving all the interior wood, as a core, inside, entire. So that by beginning with the largest size of pipe which can be bored from a piece of timber, and then boring a smaller but largest possible size of pipe from 85 the core left, and so on in the same way down to the smallest pipe used, it is seen that several joints or pieces of pipe, of different diameters, are obtained from one piece or length of timber, and the thinner 90 the pipe, the more of such joints are obtained therefrom. Augers of all the different sizes required are used for the purpose; and in laying mains and service pipes, in 95 different places, all the different sizes come into requisition. By this method of cutting out the pipes, they are made smooth and perfectly cylindrical, both inside and outside, as well as of uniform thickness.

After the joints or sections of wooden 100 pipes are thus formed, they are wound, each within a band B, generally of common hoop iron, of any requisite size and strength. The ends are fastened by screws, nails, or in any 105 secure and convenient manner. There may be separate bands or hoops for each turn around the pipe; but generally the spiral mode of winding a single band several times around each joint or section, is the simplest and cheapest method. The closeness of the 110

cords may be determined by the strength of pipe required, and in relation to the thickness of the pipe and size of the band.

The covering C, employed, is a hydraulic or other suitable calcareous cement, which will harden around the pipe, and remain close and unbroken. The preparation and use of such cements being familiar in the arts, it is unnecessary to specify the ingredients. This calcareous cement or covering fulfills a two-fold purpose in preserving the pipe.—

First, it excludes the exterior air from the wooden pipe; and the said pipe being quite thin, so that the water from inside completely saturates it through, by this exclusion of the exterior surface from the air, a continual or incessant saturation is maintained, thereby rendering the wood perpetually sound and durable, since it is well known that wood, subjected to constant, complete saturation of water, to the exclusion of atmospheric air, and the alternate evaporation and absorption consequent upon its changes, will remain sound for an indefinite or unknown length of time. And under such circumstances, if the water contains silica, or other equivalent substance, in solution, the wood may become petrified.

If it were not for this covering, the air would reach the wood, through the earth, and cause final, if not early decay.

Second, the calcareous covering effectually preserves the iron or other metallic bands, from oxidation, not only by excluding the air, on the same principle as the wood is preserved from decay, but by what is generally understood to be protection of chemical action; it being a well established fact that calcareous cement, in damp situations, almost perfectly prevents the oxidation of iron in contact with it, oxygen having a greater or stronger affinity for lime, than for iron or other metal used.

The thickness of the coat of cement should be sufficient to furnish a complete shield and protection, as above specified, and it need be no thicker. When the pipe is large, it is laid and put together in the trench, a bed of the cement, in its soft state, being put in to receive it, and then molded around it, as indicated in Fig. 4. But merchantable pipes, including service pipes and small mains, of not more than about two inches bore, are covered with the cement at the manufactory. And since the simple calcareous cement is hardly able to withstand the violence of handling and transporting, I ordinarily surround it with another coat of a bituminous composition, such as coal-tar, or asphaltum, mixed with sand, till the proper consistency is attained. This composition, being tough and adhesive, effectually preserves the ce-

ment from abrasion and disruption, so that the pipe may be even roughly handled without injury. Instead of an outer covering of the bituminous compound, it may enter, as an ingredient of the cement itself, in sufficient quantity to secure the requisite degree of cohesion.

The thimbles or short tubes D, by which the joints of the wooden pipe are coupled, have their interior diameter or bore, the same as that of the pipe itself. Their thickness is about half as great as that of the pipe. Each end of the pipe sections is bored out, (as at a, Figs. 1 and 3) just large and deep enough to receive one half of each thimble, so that when the sections are put together, the thimbles will unite them closely, strongly and smoothly, and break joints, as seen in Fig. 2. Then the swelling of the wood, when the water is let into the pipe, renders the joints perfectly water tight. Thus the interior of the pipe is continuous and even— almost as perfectly so as if in one piece. When the pipe is laid, the joints may be luted, on the outside, with the cement, so as to completely exclude the air at those places.

The thimbles D, D, are cut by annular augers, in the same manner as the wooden pipe; and also the annular rabbet spaces a, a, for the reception of the thimbles, are formed with the same kind of augers; so that the entire construction of the wooden pipes, complete for putting together is effected with the simplest machinery, in the most expeditious manner.

I am aware that the materials of which my improved water pipe is composed, have been used in the construction of water pipes, in various ways and connections. But I am not aware that they have been employed together in such united arrangement, and combination as to secure all the combined advantages afforded by my method of construction specified above. Thus, by no previous method of construction known to me, have equal thinness of the wood and consequent economy and completeness of the saturation thereof, nor equally perfect protection from decay and oxidation, nor equal effectiveness, security and simplicity in joining the pipe together, been at once attainable, while all the strength and superiority of the water pipe itself, which can be desired, is secured. Hence, while I disclaim the mere use of any and all of the materials employed, and all modes of combining them substantially different from that above described, I do assert my right to the combined construction, by which I effect these superior advantages named.

Therefore what I claim as my invention and desire to secure by Letters Patent, is—

1. The water pipe, composed of the thin

interior wooden pipe A, the metallic coils or bands B, around it, and the calcareous cement C, around the whole, (either with or without the bituminous coat or ingredient) 5 constructed and combined substantially as and for the purposes herein specified.

2. The interior wooden thimbles D, D, in

combination with the pipe constructed, substantially as and for the purpose described.

ARCALOUS WYCKOFF.
